UNITED STATES PATENT OFFICE.

GEORGE HILGER, OF CHICAGO, ILLINOIS.

AUTOMATIC VALVE-OPERATING MEANS FOR REFRIGERATION SYSTEMS.

Application filed July 26, 1924. Serial No. 728,338.

To all whom it may concern:

Be it known that I, GEORGE HILGER, a citizen of the United States, residing at Chicago, in the county of Cook and State 5 of Illinois, have invented a certain new and useful Automatic Valve-Operating Means for Refrigeration Systems.

The invention relates in general to an automatic valve operating means for refrigeration systems, and has to do more especially with the removal of oil, water and other relatively heavy matter from the anhydrous ammonia or other refrigerant prior to the discharge of the latter into the 15 condenser. Other applications of my invention will readily occur to those skilled in the art.

A special object of the present invention therefore is to provide a valve mechanism 20 which is automatically operable to separate from the refrigerating medium such elements as oil, water and other relatively heavier foreign matter, and to discharge such matter from the system automatically as it 25 accumulates.

A further object is to provide for the discharge of the separated matter into a suitable receptacle for purifying it if desired, or in the case of the collection of oil only, 30 to provide for its return to the crank case of the compressor.

In the accompanying drawings Figure 1 is an elevational view, partially diagrammatic in character, of a portion of a refrigeration system embodying my invention. 35

Fig. 2 is a vertical sectional view through the valve operating mechanism.

Fig. 3 is a fragmentary vertical sectional view taken approximately in the plane of 40 line 3—3 of Fig. 2.

Referring first to Fig. 1, 5 designates an ammonia compressor of the enclosed type embodying a crank case 6 at its base. 7 is 45 a condenser of usual or preferred construction which is connected with the compressor by a discharge line 8. 9 designates generally the means which I have produced for separating oil, water and other matter from the refrigerant before it is delivered to the condenser, this means being in the form of 50 a trap interposed in the pipe line 8. 10 designates a purifier of a suitable character which is connected with the means 9 by a pipe 11 so as to be capable of receiving 55 the oil, water, etc., which is separated out from the refrigerant. 12 is a return pipe

by which the oil separated out may, when not mixed with water and objectionable substances, be returned to the crank case 6.

The trap 9 comprises in the present instance a cylinder or casing providing a closed chamber 13. Said casing is uprightly disposed and constructed at its upper and lower ends to provide heads 14 and 15 forming pressure chambers 14' and 15'. Said heads consist of plates 16 and 17 between which and the upper and lower ends of the cylinder are interposed diaphragms 18 and 19. Between the plate 16 and the upper end of the cylinder is a plate 20 having a downwardly and inwardly projecting head portion 21 providing with the diaphragm 18 the closed chamber 14' which is adapted to contain a volatile element such as anhydrous ammonia. To form the chamber 15' at the opposite or lower end of the cylinder the latter has preferably cast therewith an inwardly and upwardly extending dome shaped head portion 22 which is closed by the diaphragm 19.

The upper inwardly projecting head portion 21 has formed integral therewith, at one side thereof, a baffle 23, and above said baffle opening into the interior of the cylinder is an inlet port 24 with which the pipe line 8 leading from the compressor communicates. On the opposite side of the cylinder near the upper end thereof is provided an outlet port 25 discharging into the opposite side of the pipe line 8 leading to the condenser. It will be apparent that the anhydrous ammonia or other refrigerant passing through the inlet port 24 from the pipe line 8 discharges against the inwardly projecting head portion 21 and the baffle 23 depending therefrom, with the result that any heavy matter carried in the refrigerant will fall to the lower portion of the cylinder while the refrigerant continues around the head portion 21 to the outlet port 25.

It will be observed that the inwardly projecting head portion 22 at the lower end of the cylinder forms with the peripheral wall in the cylinder an annular trough in which the matter thus separated out will collect. Thus the inwardly projecting portion of the head 22 serves the double function of forming the chamber 15' and also the trough 26. The chamber 15' like the chamber 14' contains a volatile element such as anhydrous ammonia. A charge of such ammonia may conveniently be admitted to the respective

chambers from the main chamber 13 by valve pipe connections 27 and 28 respectively, the valves in this instance being of a suitable hand operated type as shown at 29.

5 The pressure in the chambers 14' and 15' acting upon the diaphragms 18 and 19 respectively is transmitted to levers 30 and 31 at the opposite ends of the cylinder 13, and the levers in turn are operatively connected with a valve generally designated by the numeral 33 interposed in the pipe line 11 leading from the bottom of the annular trough 26 in the main chamber 13. The lever 30 at the upper end of the cylinder is 10 fulcrumed at one end upon a bracket 34 rigid with the cover plate 16, and a pressure member 35 bearing upon the upper face of the diaphragm 18 has a stem 36 pivotally connected with the lever 30 between its 15 ends. Similarly the lever 31 is fulcrumed on a bracket 37 and is pivotally connected to the stem 38 of a pressure member 39 engaging the under side of the diaphragm 19. The stems 36 and 38 pass through openings 20 40 and 41 respectively in the plates 16 and 17.

The valve 33 comprises in the present instance a casing 42 of ordinary construction having a valve member 43 therein controlling the passage of fluid through the casing. 30 Preferably a coiled expansion spring 44 exerts pressure upon the valve member 43 tending to hold it to its seat, and rigid with the valve member is a stem 45 mounted in the lower end of a frame 46. The frame is connected with the levers 30 and 31 so as to be movable thereby, the upper end of the frame being connected with the free end of the lever 30 by a link 47 and the lower end 35 of the frame having depending lugs 48 pivoted to the lever 31. Said lever 31 may be extended somewhat beyond its pivotal connection with the frame and provided with an adjustable weight 49. 50 is a normally open hand operated valve interposed 40 between the valve casing 33 in the pipe line 11 and the cylinder, the latter being provided in its peripheral wall with an outlet port 51 which leads from the bottom of the annular trough 26.

In operation, the chambers 14' and 15' having been previously charged with a volatile element such as anhydrous ammonia, the compressor discharges through the pipe line 8 and the inlet port 24 into the upper portion 55 of the trap against the side of the inwardly projecting head portion 21. The particles of oil, water and other heavy matter are deflected by the downward curvature of the head portion 21 and the baffle 23, so that they fall to the bottom of the trap into the annular trough 26 while the lighter refrigerating medium passes around the projecting head portion 21 and out through the port 25 and the pipe line 8 into

the condenser 7. The refrigerant thus discharged into the trap is of a substantially constant temperature and so maintains the temperature and pressure of the gas in the upper pressure chamber 14' substantially 70 constant. On the other hand the oil, water, etc., falling into the trough 26 in the lower end of the trap and accumulating therein exposes to a gradually decreasing degree the chamber 15' to the head of the refrigerant, 75 and thus effects a reduction in the temperature of the volatile element in the pressure chamber 15'. The arrangement is such that as the foreign matter accumulates to a pre-determined extent, the constant pressure in the chamber 14' acting upon the lever 30, 80 will overcome the pressure in the chamber 15' acting upon the lever 31 plus the weight 49 on the lever, with the result that the valve 33 is opened to permit the passage of the accumulated fluids into the pipe line 11. In this connection, it will be observed that the interior of the cylinder 13 forming the trap is constantly under pressure so that when the valve 33 is opened the segregated matter is forcibly discharged therethrough. Moreover, as soon as the collected matter is 85 discharged sufficiently to expose the interior of the inwardly projecting head portion 22 to the hot gases, the temperature and pressure in the pressure chamber 15' rise to effect a closing of the valve 33.

It will thus be seen that I utilize the accumulation of the foreign substances separated out from the refrigerant or other carrying medium to produce a difference in temperature in the two opposed pressure chambers, and the resulting difference in pressures is utilized to operate the valve. Conversely the discharge of the matter separated out results in the restoration of the pressures in the opposed chambers to normal and thus effects a closing of the valve. 100

It is especially desirable to separate out the oil, which is present in the largest proportion, and in some instances the presence of other foreign matter is practically negligible so as to permit of the immediate reuse 110 of the oil. It is thus practicable, in cases employing compressors of the closed type, wherein the oil is supplied to the crank case, to return the oil separated out directly to the crank case, and this is accomplished in the present instance by the pipe line 12. The latter connects with the pipe line 11 and communication is controlled by means of a hand operated valve 52. 115

To determine when the valve 52 may be operated to connect the pipe line 12 with the pipe line 11, I provide a sight glass 53 upon the exterior of the trap cylinder which communicates with the main chamber 13 in the usual way. This glass, it will be apparent, because of the tendency of water and 120

5 sediment to segregate from the oil, readily indicates whether or not the oil accumulation in the trough 26 is of such a character as to be capable of direct return to the crank case.

10 In the event that it is not practicable to return the oil to the crank case, I provide for its discharge into the purifier 10 and to this end the valve 52 is of the three-way type. Inasmuch as the construction of this valve may be of any suitable character it is deemed unnecessary to illustrate and describe its construction in detail.

15 The purifier 10 may be of any preferred or usual construction. In the present instance it consists of a tank 54 into the lower end of which the pipe line 11 discharges. The upper end of the tank leads by way of a pipe 55 to the suction or return line 56 20 of the system which is connected to the inlet side of the compressor. Thus the pressure in the purifier corresponds substantially to the pressure in the return line 56, which being substantially lower than the condenser pressure produces a condition in the purifier 25 10 such that any portion of the refrigerant which may have passed through the trap 9 to the purifier will be vaporized and drawn off through pipe 55 and returned to 30 the compressor. The residue may be conveniently drawn off through the bottom of the tank through the valved outlet pipe 57. If desired the purifier may be provided with a gaseous fuel burner 58 to assist in the 35 vaporization of the refrigerant; and a sight glass 59 may be provided on the tank 54 to indicate the character and volume of the matter collected in the purifier.

40 It will be apparent that I have provided means of an advantageous character for separating one or more elements of a gas or fluid from another, and while it is contemplated that such means may be capable of general application it is especially of value 45 as applied to a refrigerating system and especially to the separating out from the refrigerating medium of foreign substances which as in the present instance may be capable of reuse so that efficiency of the 50 system as a whole is increased while the cost of operation is reduced due to the reclamation of the lubricant.

I claim as my invention:

55 1. A trap for removing foreign matter from a gaseous system comprising, in combination, a casing having an inlet for the gaseous mixture and outlets for gas and foreign matter, a valve controlling the outlet for foreign matter, means for separating said gas and foreign matter within said casing, said casing being adapted to collect the foreign matter, and an element exposed to the foreign matter collecting in said casing and responsive to the temperature thereof 60 for controlling said valve.

2. In a refrigeration system a trap adapted to receive the refrigerating medium under pressure, means causing the separation of foreign matter from the refrigerating medium, and thermo-responsive means operable 70 automatically upon an accumulation of such foreign matter to permit its discharge from the trap.

3. In a refrigeration system a trap adapted to receive the refrigerating medium under pressure, means causing oil and other foreign matter to separate out from the refrigerating medium, and means operable automatically upon an accumulation of such foreign matter to permit the discharge from the trap 75 comprising a pair of opposed pressure chambers both of which are initially subject to the temperature of the refrigerating medium discharged and one of which is subject to temperature variation due to the accumulation of the foreign matter separated out.

4. In a refrigeration system a trap adapted to receive the refrigerating medium under pressure, means causing certain foreign matter to separate out from the refrigerating medium, and means operable automatically 90 upon an accumulation of such foreign matter to permit the discharge from the trap comprising a pair of opposed pressure chambers both of which are initially subject to the temperature of the refrigerating medium discharged and one of which is subject to temperature reduction due to the accumulation of the foreign matter separated out.

5. In a refrigeration system a trap adapted to receive the refrigerating medium under pressure, means causing certain foreign matter to separate out from the refrigerating medium, and means operable automatically 100 upon an accumulation of such foreign matter to permit the discharge from the trap comprising a pair of temperature responsive elements both of which are initially subject to the temperature of the refrigerating medium discharged and one of which is subject to temperature reduction due to the accumulation of the foreign matter separated out, and a valve arranged to be operated by the one of said elements when the difference in temperatures varies to a predetermined 110 extent.

6. A trap for removing a foreign liquid from a gaseous system under pressure comprising, means for separating the liquid from the gas within said system, valve-controlled means for discharging the collected liquid from the system, and means responsive to a predetermined temperature difference between said gas and the liquid collected for opening and closing said valve.

7. A trap for removing foreign matter from the refrigerant in a refrigeration system comprising, in combination, a casing providing a chamber in communication with said system so as to receive a mixture of re-

frigerant and foreign matter, means for separating the refrigerant from the foreign matter within said chamber, said casing being adapted to collect the foreign matter thus separated so as to effect a cooling thereof, a valve-controlled outlet from said casing for said foreign matter, and means responsive to a decrease in the temperature of said foreign matter for operating said valve.

10. 8. The method of removing a foreign liquid from a gaseous refrigerant in a refrigeration system which consists in separating the liquid from the gaseous refrigerant, collecting the liquid and effecting a cooling thereof, and discharging the liquid from the system under the control of the temperature difference between the liquid collected and the gaseous refrigerant.

15. 9. The method of removing a foreign matter from a gaseous system which consists in separating the foreign matter from the gas, collecting the foreign matter and effecting a cooling thereof, and discharging the foreign matter under the control of its own temperature.

20. 10. In a refrigeration system, the combination with a pipe line conveying a gaseous refrigerant, of a trap interposed in the pipe line and adapted to effect a separation of oil from the refrigerant, and means automatically operable to discharge the oil from the trap, the means for effecting the discharge of oil comprising a pair of opposed temperature responsive elements and 25 a discharge valve operatively associated with said elements, both of said elements being initially subject to the temperature of the refrigerant and one of said elements being exposed to the refrigerant to a gradually decreasing degree as the foreign matter accumulates, the arrangement being such that the difference in temperatures produced causes the operation of said valve.

30. 11. A trap for refrigeration systems having an inlet adapted to communicate with the discharged side of a compressor and an outlet adapted to communicate with a condenser, said trap being adapted to effect the separation of foreign matter from the refrigerant, means providing two temperature responsive pressure chambers in the trap, one of said chambers being at all times subject to the temperature of the refrigerant as it is discharged and the other one of said chambers being exposed to such temperature to a gradually decreasing degree by the collection of foreign matter in the trap, and a valve for controlling the discharge of oil from the trap, said valve being operatively associated with said pressure chambers so as to be operable thereby when the difference in pressures in the two chambers reaches a predetermined point.

35. 12. A trap for refrigeration systems adapted to segregate foreign matter from

the refrigerant, means providing two temperature responsive elements in the trap, one of said elements being at all times subject to the temperature of the refrigerant as it is discharged and the other one of said elements being exposed to such temperature to a gradually decreasing degree by the collection of foreign matter in the trap, a valve for controlling the discharge of foreign matter from the trap, and means including a lever connecting said valve with each of said elements whereby when the difference in temperatures between the two elements reaches a predetermined point the valve will be opened.

40. 13. A trap for refrigeration systems having an inlet and adapted to segregate foreign matter from the refrigerant, means providing a temperature responsive element in the trap exposed to the temperature of the fluid entering the trap through said inlet to a gradually decreasing degree by the collection of oil in the trap, and a valve operatively connected with said element for controlling the discharge of oil from the trap upon a reduction in the temperature of said element to a predetermined point.

45. 14. A trap for refrigeration systems adapted to segregate foreign matter from the refrigerant, means providing two temperature responsive elements in the trap, one of said elements being at all times subject to the temperature of the refrigerant as it is discharged and the other one of said elements being exposed to such temperature to a gradually decreasing degree by the collection of foreign matter in the trap, a valve for controlling the discharge of foreign matter from the trap, means including a lever connecting said valve with each of said elements whereby when the difference in temperatures between the two elements reaches a predetermined point the valve will be opened, and adjustable means for determining the temperature difference effecting the operation of the valve.

50. 15. A trap having an inlet and an outlet for a fluid containing an element to be separated out by gravity, means in the trap for effecting the separation of such element, a pair of temperature responsive elements one of which is at all times exposed to the temperature of the fluid discharged into the trap and the other one of which is exposed to a gradually decreasing degree to the temperature of such fluid by reason of the accumulation of the separated element, and means operatively associated with said elements and adapted to effect the discharge of the separated matter when the temperature difference between the two elements reaches a predetermined point.

55. 16. The combination of a trap having an inlet and an outlet for a fluid containing matter to be separated therefrom, means for

discharging the fluid into the trap at a high and substantially constant temperature, means for effecting a separation of said matter from the fluid, and thermo-responsive 5 means automatically operable upon an accumulation of such matter to effect its discharge from the trap.

17. A trap having an inlet and an outlet for a fluid containing matter to be separated therefrom, means for discharging the fluid into the trap at a high and substantially constant temperature, means for effecting a separation of said matter from the fluid, and means automatically operable upon an accumulation of such matter to effect its discharge from the trap comprising a pair of chambers each containing a volatile element, both of said chambers being initially subject to the temperature 20 of the heated fluid and one of said elements being adapted to be surrounded by the separated matter to a gradually increasing extent so as to expose it to the temperature of the heated fluid to a gradually 25 decreasing extent as the matter accumulates, and means operable when the temperature difference between the chambers reaches a predetermined point to effect the discharge of the separated matter.

30 18. A trap adapted to receive a fluid at relatively high temperature and containing matter to be separated therefrom, means providing a pair of opposed temperature responsive pressure elements, one of said 35 elements being maintained at a temperature substantially equal to the temperature of the fluid and the other one of said elements being subject to the gradually lowering temperature of the separated matter, 40 and means operatively associated with said elements and operable when the temperature difference between said elements reaches a predetermined point to effect the release of the separated matter.

45 19. The combination with a source of supply of a heated element in fluid form, of a trap into which said element is adapted to discharge and to accumulate, a temperature responsive device subject to the gradually 50 decreasing temperature of said element, and means operable upon the accumulation of a predetermined volume of such element in the trap to effect its discharge therefrom.

55 20. The combination with a source of supply of a heated element in fluid form, of a trap adapted to receive said element for accumulation, a temperature responsive device subject to the gradually lowering temperature of said element as it accumulates, discharge means including a valve, and means for exerting a substantially constant opposing force upon said valve whereby to open it as the pressure upon said device falls due to the accumulation of said 60 element.

21. The combination with a source of supply of a heated element in fluid form, of a trap adapted to receive said element for accumulation, a pair of pressure chambers in said trap each containing a volatile 70 element, a lever operatively associated with each chamber, and a valve connected with said levers, the arrangement being such that as the element accumulates in the trap it effects a gradually lowering temperature 75 of one of said pressure chambers whereby to permit the pressure in the other chamber to open the valve.

22. The combination with a source of supply of a heated element in fluid form, 80 of a trap adapted to receive said element for accumulation, a pair of pressure chambers in said trap each containing a volatile element, a lever operatively associated with each chamber, and a valve connected with 85 said levers, the arrangement being such that as the element accumulates in the trap it cools and gradually lowers the temperature of one of said pressure chambers whereby to permit the pressure in the other chamber 90 to open the valve, one of said levers having adjustable means for varying the point at which said valve is opened.

23. In a refrigeration system, the combination of means providing a main chamber 95 adapted to receive the refrigerant under pressure, a pair of temperature-responsive pressure chambers projecting into the opposite ends of said main chamber, one of said pressure chambers providing with the outer wall of the main chamber an annular trough and the other one of said pressure chambers providing a wall against which the refrigerant is adapted to discharge to effect the separation out of oil and other 100 foreign matter and to cause it to accumulate in said trough, and valved means operatively associated with said pressure chambers so as to permit the discharge of accumulated 105 matter from the main chamber when a predetermined quantity of such matter has accumulated in said trough.

24. A trap having in combination with a source of supply of heated fluid, a temperature-responsive pressure chamber, means 115 adapted to collect such fluid and to effect a gradually lowering temperature in said chamber, and means operating when a predetermined temperature reduction in said chamber is reached to effect the discharge 120 of the fluid from the trap.

25. A trap having in combination with a source of supply of heated fluid, a pair of temperature responsive pressure chambers both of which are initially subject to the 125 temperature of the fluid and one which is adapted to be exposed to a gradually decreasing extent by the accumulation of such fluid in the trap, a discharge valve for the trap, a lever connected with each of said pressure

chambers so as to be movable thereby and also connected with said valve, the arrangement being such that normally said pressure chambers are balanced against each other but when a predetermined difference between the two chambers is reached owing to the accumulation of such fluid, the valve is operated to permit the discharge of the fluid from the trap.

10 26. A trap having a main chamber having heads at upper and lower ends with portions projecting into the main chamber, said heads each containing a volatile element and including a movable wall, the main chamber having communication with a source of heated fluid and said head portion being subject to the temperature of said fluid, the arrangement being such that the fluid accumulating in the trap effects a gradual 20 lowering in the temperature in one of said chambers, a discharge valve for the trap, and means connecting the movable walls of said pressure chambers to said valve.

25 27. A trap comprising a main chamber having heads at the upper and lower ends with portions projecting into the main chamber, said heads each containing a volatile element and including a movable wall, the main chamber having communication with a source of heated fluid and said head portions being subject to the temperature of said fluid, the arrangement being such that the fluid accumulating in the trap cools slowly and thereby effects a gradual lower-

35 ing in the temperature in one of said chambers, a discharge valve for the trap, and means connecting the movable walls of said pressure chambers to said valve comprising a lever fulcrumed on each head and having a pressure member bearing against the movable wall of the corresponding pressure chamber, and means pivotally connected to said levers and arranged to operate said valve.

40 28. A trap comprising a main chamber having heads at the upper and lower ends with portions projecting into the main chamber, said heads each containing a volatile element and including a movable wall, the main chamber having communication with a source of heated fluid and said head portions being subject to the temperature of said fluid, the arrangement being such that the fluid accumulating in the trap effects a gradual 45 lowering in the temperature in one of said chambers, a discharge valve for the trap, and means connecting the movable walls of said pressure chambers to said valve comprising a lever fulcrumed on each head and having a pressure member bearing 50 against the movable wall of the corresponding pressure chamber, and means pivotally connected to said levers and arranged to operate said valve, one of said levers having 55 adjustable weights thereon.

60 In testimony whereof, I have hereunto affixed my signature.

65 GEORGE HILGER.
